[57] CLAIM

An ornamental design for an original feeder for copying machine, substantially as shown and described.

DESCRIPTION

FIG. 1 is a perspective view of an original feeder for copying machine showing our new design;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a right side elevational view thereof;
 FIG. 7 is a left side elevational view thereof; and
 FIG. 8 is a perspective view thereof, the broken-line showing of a copying machine is environmental only and forms no part of the claimed design.

FIG. 1

FIG. 2

FIG. 3
